UNITED STATES PATENT OFFICE.

MATTHIAS BROCK, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

TOE-SOFTENING MACHINE.

1,373,481.

Specification of Letters Patent.

Patented Apr. 5, 1921.

Application filed February 28, 1917. Serial No. 151,587.

To all whom it may concern:

Be it known that I, MATTHIAS BROCK, a citizen of the United States, residing at Boston, in the county of Suffolk and State 5 of Massachusetts, have invented certain Improvements in Toe-Softening Machines, of which the following description, in connection with the accompanying drawings, is a specification, like reference characters on 10 the drawings indicating like parts in the several figures.

This invention relates to apparatus for treating shoes and especially to devices used in treating shoes or portions of them 15 by heat or moisture, or both, in preparation for the lasting operation.

It has been found that the lasting operations at those portions of the shoe where the upper materials have to be crimped and 20 stretched to conform to the last (for instance at the toe) can be greatly facilitated by the administration of certain softening treatments to those portions of the shoe. These treatments are almost as varied as 25 the shoe materials themselves. Some materials respond to dampening with water; some to dampening with steam, these again differentiating as to the temperature and dryness of the steam or vapor used; other 30 materials require only the use of much drier heat, to which the "self hardening" or "Beckwith" toe box will respond.

Various devices have been proposed for administering these treatments to the shoes, 35 but they are all subject to the objection of lack of flexibility in meeting the widely varying conditions under which these devices have to work. The shoes that come to the operatives in the course of a day's run 40 differ, one from another, in color and material, requiring radically different treatment, so that heretofore a multiplicity of softening devices, differing as to the character of treatment, has been necessary to treat the 45 entire factory output. A demand has therefore arisen for a device that will administer dry or damp treatment at a wide range of temperature to the shoe, and it is a principal object of my invention to provide a machine that will fulfil this demand.

It has become settled that any practical "universal" softening device must contain means for administering vapor treatment to the shoe. A vapor obtained from steam at low pressure, or from boiling water, is 55 at a temperature of approximately 212° F. It becomes more or less cooled and condensed or "wet" in transmission to the shoe, and, although some materials demand it in this condition, others require heat with com- 60 paratively little or no moisture. Extreme heat can of course be obtained from steam at sufficiently high pressure, but such steam is not ordinarily available for this purpose in shoe factories, and it is difficult, if not 65 impossible, to use it without burning the work.

In accordance with this invention a dry-heating device is provided for superheating a vapor of initially low temperature, such 70 heating device being controlled to generate heat at a wide range of temperature. Accordingly, an important feature of the invention comprises a novel organization of means for supplying moderately warm vapor to the shoe, and means for substantially 75 heating the vapor.

Another feature of the invention involves a novel and improved relation of the vapor-supplying means and the dry heat generator, and the relation of both to the work. According to this feature, as shown, the vapor-supplying means is arranged to supply the vapor below the work so that the vapor will proceed to the work by levitation and envelop the work before it can escape. The dry heat generator is arranged above the vapor-supplying means and in proximity to the work so as to heat the latter by direct radiation. Furthermore, the 90 dry heat generator is so disposed that the vapor will pass between it and the work before reaching any outlet through which it may escape. This relative arrangement has several advantages among which are the 95 following:—The vapor, without being forced, will, in all cases, temper the dry heat so as to guard against burning or drying the work; the dry heat will amplify the penetrability of the vapor; and the wasting 100

of vapor is minimized. The latter advantage, aside from the mere economy of vapor, is important for the additional reason that it avoids producing a humid atmospheric condition in the work-room, which is both unhealthful and rust-producing.

A device of this character should be capable of discontinuing or beginning the vapor supply abruptly. No time should be lost in generating vapor after the machine has been used as a dry heater, or in stopping the delivery of vapor when a rack of shoes requiring only dry heat comes to the machine. My invention also provides this feature of flexibility.

Another difficulty frequently met in machines of this type is that colored shoes soil those portions of the apparatus on which they rest, especially those portions which contact the treated parts of the shoes, from which the color rubs off most readily. To overcome this difficulty the present invention provides a work-support having a plurality of separate work-engaging surfaces that may be used respectively for one color only, by shifting the work-support according to the color of the shoe about to be treated.

These and other features of the invention, comprising various combinations and arrangements of parts, will be best understood and appreciated from the following description of a preferred embodiment thereof selected for purposes of illustration by the accompanying drawings, in which,—

Figure 1 is a transverse sectional view of the machine;

Fig. 2 shows in detail the arrangement of the upper electric units;

Fig. 3 is a broken away front elevation;

Fig. 4 shows a lower unit;

Fig. 5 is a detail of the toe rest, and

Fig. 6 is a plan of the adjustable support.

The casing 10, which may be conveniently made in two parts as shown, comprises a chamber 12, at the top of which a reduced channel 14 opens into an upper chamber 16 which has an opening 18 for the reception of the shoe toes. The passage 14 may contain a diaphragm 19 of netting or waste for checking and cooling the vapor from the chamber 12, and may be closed by a baffle or gate 20, pivoted at 22, which has an open and a closed position as shown. The gate and the channel 14 extend the whole length of the apparatus.

A wooden bar 24, having headed pins 26 which rest in notches 28 in the lower front wall of the chamber 16, projects above the lower edge of the opening 18 and supports the toes of the shoes being treated. As the bar is often in contact with damp or wet portions of the shoes, and is likely to become stained by the coloring materials in them, the pins 26 are equally and symmetrically

spaced so that the bar 24 may be turned end for end and placed upside down, thus affording two supporting surfaces, 30, 32, for shoes of contrasting colors. One surface may be used for black shoes and the other for tans, or a plurality of interchangeable bars may be provided, affording a wide range of accommodation.

The upper chamber contains a casing 34 having a large radiating surface in which are mounted two electric units 36, 38 end to end. These may be supplied with suitable rheostats as at 39, whereby their temperature may be controlled. The use of two small units rather than one large one gives somewhat more flexibility in temperature regulation, since low temperatures can be obtained with one unit, and a large rheostat with a large number of steps is not required as in the case of the double size unit.

The lower chamber 12 contains a casing 40 in which two electric units 42 are arranged, end to end. These may also be controlled by suitable rheostats not shown. A steam pipe 44 having perforations 46 is mounted in the lower part of the lower chamber, and its steam supply is controlled by a suitable valve 47.

On the rear side of the machine is a barometric water feeding device 48 having a removable can 50, supported from the casing by a bail 52. The feed water passes through a pipe 54 into the lower chamber, where the feeder 48 maintains it at constant level. A valve 55 and drain cock 57 are provided for shutting off the water and draining the chamber.

In the upper part of the upper chamber 16 is an opening 56 adapted to be closed by an adjustable gate 58, in order to control the passage of air or vapor through the apparatus. A drain pipe 60 extends from the rear bottom part of the chamber 16 down through the chamber 12 and opens into the drain cock 57. This carries away any moisture which condenses in the chamber 16.

The shoe support 62 is shown as a rod bent into a series of parallel loops lying in the same plane, with its ends pivotally supported in two ears 64. The middle portion of the support is also pivoted to two arms 66, mounted on the casing. Struts 72 are pivotally attached to the outer ends of the loops, and have their downturned ends 74 inserted in one of two series of holes 76 and 78 in the flange 80. These two series of holes permit two corresponding adjustments of the support 62 adapted for shoes in inverted and in upright position, respectively as shown in Fig. 1. It is desirable to get the material to be treated as close to the treating means as is consistent with safety. A support which tilts the shoe at the proper angle in the upright position may throw the box too far toward the electric units when

the shoe is inverted, if the box is very high, and I have accordingly made my support so that it can be tilted down to hold a high box in proper relation to the electric units.

5 A rod 82 carrying a slider 84 is arranged over the opening 18, the slider enabling the operator to mark the position of the next shoe to be taken from the apparatus. The upper edge of the opening 18 is formed with 10 a slope, as at 86, to facilitate the transfer of condensed moisture to the sides of the chamber, so that it may drain away instead of dropping on the shoes. The whole machine may be conveniently supported on a 15 base 88.

My novel apparatus may be used in many ways. The chamber 10 may be supplied with vapor from the steam pipe 44, the water supply from the feeder 48 being cut 20 off, and the chamber 10 drained through the valve 57. Steam of substantially the quality present in the supply line will be supplied to the apparatus from the steam pipe 44, and the gate 20 being open, will be applied 25 to the shoes in position on the support 62. This steam may be dried and even super-heated, if desired, by means of the units 42, from which, by means of rheostats, a wide range of temperature may be secured. The 30 units 38 may also be used to superheat the vapor after it passes through the channel 14.

Wet steam may be obtained by allowing the feeder 48 to supply water to the chamber 12, this water being heated by steam 35 from the pipe 44 or by the units 42. Rapid ebullition in the generation of steam will produce a wet vapor and the rapidity of generation may be easily controlled by the valve or the rheostats.

40 The supply of vapor to the chamber 16 may be instantly begun or discontinued or, as set forth in the appended claims, "limited" by manipulating the gate 20. No time need therefore be lost between the treatment of two racks of dissimilar shoes.

In case dry heat only is required for the 45 shoes, as might be the case where a delicate leather or a fabric is used, preferably in combination with a "Beckwith" box, the gate 20 may be closed and the units 38 energized to supply the heat at the temperature required. Vapor may be slowly generated in the chamber 10 and admitted to temper 50 such dry heat if desired. The passage of the heat and moisture carrying media over and around the shoes may be controlled to a certain extent by the closure 58.

I have thus provided a softening machine 55 having a wide range in temperature and modes of treatment of the shoes. My machine performs the different sorts of work done by many machines of various types now found on the market, in addition to being capable of results not heretofore obtainable.

Having described the invention, what I claim as new and desire to secure by Letters Patent of the United States is:

1. A shoe-treating apparatus comprising a treating device having a vaporizing chamber, vaporizing means arranged therein below the treating locality, and means arranged to heat the vapor rising from said vaporizing means to the treating locality. 70

2. A shoe-treating apparatus comprising a treating device having a chamber, means for generating vapor therein below the treating locality, and means for radiating dry heat therein below the treating locality. 75

3. A shoe-treating apparatus comprising a treating device having a chamber, electrical means for generating vapor therein below the treating locality, and means for heating the vapor rising from said electrical means to the treating locality. 80

4. A shoe-treating apparatus comprising a treating device having a chamber for containing a body of liquid, means arranged in said chamber to vaporize said liquid, and means arranged to heat the vapor rising 90 from the first said means.

5. A shoe-treating apparatus comprising a treating device having a chamber, so that the heat generated thereby will radiate to the work, and means arranged to generate vapor in said device under said location so that the vapor thereby generated will have an unobstructed path in which to rise therefrom to the work, and heat-radiating means arranged in said chamber below the level 100 of the work. 95

6. In a machine of the class described, a treating device having a chamber, an electric unit arranged therein adjacent to the position occupied by the shoe, said device 105 having a channel for conducting vapor to the vicinity of the shoe being treated, and means in said device for closing said channel whereby the vapor treatment of shoes may be regulated. 110

7. A shoe-treating apparatus comprising a treating device, and shoe-supporting means arranged to support a shoe in upright position or to hold it in inverted position for treatment, said means being adjustable to various angles according to whether the shoe occupies upright or inverted position. 115

8. A shoe-treating apparatus comprising means for administering treatment, an adjustable member adapted to sustain a shoe in upright position or to hold the shoe in inverted position in a treating locality, and means constructed and arranged to sustain said member at various angles according to 120 whether the shoe is upright or inverted.

9. A shoe-treating apparatus comprising a treating device, and a work-support having a plurality of separate work-supporting portions, said work-support being shiftable 130

to different positions to locate said portions at will in a common work-engaging position, whereby discoloring of the work by said work-support may be avoided in sequence of shifting the work-support according to the color of successive pieces of work.

10. In a machine of the class described, a casing having means for treatment of a shoe and means for supporting a shoe in operative relation to said treating means, said supporting means being shiftable to different positions and having a plurality of surfaces arranged alternatively to contact with the shoe according to the position occupied by said supporting means, whereby shoes of one color may be supported otherwise than by a surface that has become colored by contact with shoes of another color.

15. A shoe-treating apparatus comprising a treating device, and a detachable work-supporting device arranged to engage a portion of the work presented for treatment, said devices having coöperative interlocking portions arranged to maintain them normally in coöperative relation but being freely separable to permit detaching the work-supporting device.

20. 11. A treating apparatus comprising means forming a treating chamber, means for supplying vapor to said chamber, heat-radiating means arranged in the chamber, and adjustable means arranged to baffle the vapor and the radiated heat, alternatively.

25. 12. A treating apparatus comprising means forming a treating chamber, means for supplying vapor to said chamber, heat-radiating means arranged in the chamber, and adjustable means arranged to control the vapor and the path of the radiated heat.

30. 13. A treating apparatus comprising means forming a treating chamber, means for supplying vapor to said chamber, heat-radiating means arranged in the chamber, and adjustable means arranged to control the vapor and the path of the radiated heat.

35. 14. A treating apparatus comprising means forming a treating chamber, means for supplying vapor to said chamber, heat-

radiating means arranged in the chamber, and means arranged to control the escape of vapor and to divert the radiated heat.

40. 15. A treating apparatus comprising means forming a treating chamber, means for supplying vapor to said chamber, heat-radiating means arranged in the chamber, and an adjustable member arranged to guide the vapor and the radiated heat in separate courses.

45. 16. A treating apparatus comprising means forming a treating chamber, means for supplying vapor to said chamber, heat-radiating means arranged in the chamber, and means arranged to be movable so as to throttle the vapor and baffle the radiated heat, alternatively.

50. 17. A treating apparatus comprising means forming a treating chamber, heat-radiating means arranged in the chamber, means for supplying vapor to said chamber, and means arranged between the heat-radiating means and the locality of the work for regulating the vapor and the radiated heat.

55. 18. A treating apparatus comprising means forming a treating chamber, heat-radiating means arranged in the chamber, means for supplying vapor to said chamber, and adjustable means arranged to be heated by the radiated heat and to control the vapor between the vapor-supplying means and the locality of the work.

60. 19. A treating apparatus comprising means forming a treating chamber, heat-radiating means arranged in the chamber, means for supplying vapor to said chamber, and an adjustable baffle arranged to vary inversely the channels of escape of the vapor and the radiated heat.

In testimony whereof I have signed my name to this specification.

MATTHIAS BROCK.
